UNITED STATES PATENT OFFICE.

CHARLES E. GIBSON, OF CONWAY, NEW HAMPSHIRE.

DESIGN FOR A DOLL.

SPECIFICATION forming part of Design No. 33,717, dated December 11, 1900.

Application filed September 20, 1900. Serial No. 30,634. Term of patent 14 years.

To all whom it may concern:

Be it known that I, CHARLES E. GIBSON, a citizen of the United States of America, and resident of North Conway, Carroll county, 5 State of New Hampshire, have invented and produced a new and original Design for Dolls, of which the following is a specification.

My invention relates to a design for a doll adapted to be sold and used as a souvenir.

10 The design is shown in the accompanying drawings, in which—

Figure 1 is a perspective view of my doll, and Fig. 2 is a side view of the same.

15 A represents a board tapering from the head to the foot and having the head end a rounded.

B represents the doll proper, here shown as having a face and hair to represent an Indian papoose. The doll is shown as strapped to the 20 board A by means of a wide strap C, which extends from the doll's head to a point near the foot end of the board. The strap C is represented as passing around the board laterally, the two ends meeting in the center line

of the board and being fastened together by 25 means of the lacing d, tied in a bow at the top.

The head of the board is ornamented by a line of scallops b, parallel with the edge, with notches formed in the edge, and the foot of the board has similar notches and has also 30 two curved lines e e, parallel with the edge, or nearly so, with radial lines f extending upward from the upper curved line. The upper edges of the straps are fringed and on each side, near the top, is a substantially 35 round dot G, with an elongated crescent h adjacent thereto and a series of diagonal lines extending across the face of the strap and inclining toward the edge.

I claim—

40 The design for a doll substantially as herein shown and described.

Signed at North Conway, New Hampshire, this 12th day of September, 1900.

CHAS. E. GIBSON.
